PORTABLE VISE HAVING A NUT-OPERATED
JAW PIVOTALLY MOUNTABLE IN A SE-
LECTED FULCRUM APERTURE

Thomas R. Evans, Sumter, S. C.

Application November 19, 1946, Serial No. 710,912

3 Claims. (Cl. 81—19)

1

My invention relates to a portable vise.

Important objects of the invention are to provide for holding and automatically centering workpieces which may be circular or elliptical in cross section; to provide a device embodying adjustable parts which may be separated and knocked down for compact assembly when not in use; and to provide a device which is relatively simple and has a large range of adjustments.

In the accompanying drawings forming a part of this application and in which like numerals are employed to designate like parts throughout the same,

Figure 1 is a perspective view of a portable vise embodying my invention.

Figure 2 is a transverse section taken on line 2—2 of Figure 1.

Figure 3 is a rear side elevation of the vise, parts removed.

Figure 4 is a plan view of the vise, parts removed, showing the same mounted upon a metal plate.

Figure 5 is a similar view showing the vise mounted upon a wooden support.

In the drawings, wherein for the purpose of illustration is shown a preferred embodiment of my invention, the numeral 10 designates the body portion of the vise, which is preferably formed of an angle iron, having a horizontal web 11 and a vertical web 12. Rigidly mounted upon the rear face of the vertical web 12 are upper and lower pairs of horizontal V-shaped jaws 13 and 14, tapering rearwardly from the vertical web 12 and having their open end welded or otherwise rigidly secured to the vertical web 12. The apices 15 of these jaws are preferably pointed or sharp so that they will readily sink into a tree or other wooden support and will also more readily grip with a hard metal support. These jaws, by sinking into the tree or wooden support, when used with the associated means, serve to securely grip the body portion 10 to the tree or the like, preventing the body portion from turning or slipping, and in addition, serve to space the body portion from the tree or support, thereby rendering it more convenient to manipulate the object being held. As more clearly shown in Figure 3, the vertical web 12 has openings 16, the centers of which are in alignment with the edges 15 of the jaws 13. The web 12 also has an intermediate opening 17, the center of which is in alignment with the transverse center of the vertical web 12. These openings are adapted to receive bolts, for a purpose to be described.

2

One end of the vertical web 12 is slit longitudinally, as shown at 18, Figure 1, adjacent to the horizontal web 11, and is bent forwardly slightly providing a forwardly horizontally inclined portion 19, having a longitudinal slot 20. This slot 20 is adapted to receive a selected link of a chain 21, for interlocking engagement therewith, as shown. By virtue of the horizontal forward inclination of the portion 19 the link will not slide outwardly from the slot 20 when the chain is tightened up, in the event that the tree should have a diameter larger than the space between the points of connection of the chain with the vertical web. At its opposite end the chain is attached to an eye 22 carried by a bolt 23 passing through an elongated opening 24 in the opposite end of the vertical web 12. This bolt passes through washers 25 and is engaged by a tubular nut 26, having screw-threaded engagement therewith. The tubular nut is turned by a handle 27.

Mounted upon the horizontal web 11 near its ends and preferably at the central longitudinal axis of the web 11 are upstanding open V-shaped jaws 28, which diverge upwardly, and have their apices lowermost and rigidly attached to the web 11 by welding or the like. These jaws are preferably arranged near the ends of the web 11 to receive and engage the work at remote points, whereby the maximum leverage is obtained for holding the work or handle against lateral displacement.

The body portion 10 is provided at its top and at the apex produced by the horizontal and vertical webs 11 and 12 with a ring 29 passing through openings 30 and 31, and this ring is passed through an elongated opening 32 formed in a strap 33 having additional openings 34, spaced longitudinally of the strap. When the vise is to be stored away, the strap 33 is adapted to be folded down upon the horizontal web 11. The openings 30 and 31 are in vertical alignment with the opening 17 and are at the transverse center of the body portion 10.

Coacting with the upwardly facing V-shaped jaws 28 is an inverted V-shaped jaw 35, diverging downwardly and having its apex arranged uppermost. A V-shaped rod 36 is arranged upon the top of the inverted V-shaped jaw 35 and is welded or otherwise rigidly secured thereto. At the rear the rod 36 has an extension or hook 37 which is adapted to be inserted into the elongated opening 32 or a selected opening 34. At its forward end, the rod 36 has an eye 38, engaging within an eye 39, formed upon a screw-threaded bolt 40,

passing downwardly through an elongated opening 41, formed in an ear 42, rigidly secured to the forward edge of the horizontal web 11. The bolt 40 extends downwardly below the ear 42 and passes through washers 43 and engages with a tubular nut 44, having space 45 to receive a lubricant such as grease. This tubular nut is turned by a handle 46. The tubular nut 26 is preferably identical with the tubular nut 45. The invention is not restricted to the arrangement of the rod 36 above the jaw 35 and welded thereto as the hook 37 and eye 38 could readily be formed integral with the ends of the jaw 35. Various other details of construction can be varied, as is obvious.

The operation of the vise is as follows:

When it is desired to apply the vise to a tree, the rear side of the body portion 10 is brought next to the tree so that the apices or pointed ends of the jaws 13 will engage the tree. The free end of the chain is passed about the tree and drawn close to the same and a link of the chain 21 is then inserted within the slot 20 of the inclined portion 19. Should the diameter of the tree be larger than the distance between the points of connection between the chain and the body portion 10, the inclination of the portion 19 will prevent the link slipping out of the slot 20 when the chain is tightened up. The handle 27 is now turned and the tubular nut screwed up upon the bolt 23, which is drawn forwardly drawing the chain with it and tightening up the same. The opening 24 being horizontally elongated, the bolt 23 can angularly adjust itself in accordance with the diameter of the tree. When the chain 21 is tightened up sufficiently the apices of the jaws will embed themselves in the tree and the body portion will be clamped to the tree so that it will not slip or turn thereon.

If it should be desired to mount the body portion upon a metal plate 47 secured to a truck body or the like, the chain 21, bolt 23, and tubular nut 26 may be separated from the body portion 10. Bolts 48 are now passed through the openings 16 and through openings in the plate 47 and the jaws 13 and 14 clamped to the plate 47 by screwing up nuts 49 on the bolts 48. This is shown in Figure 4.

In Figure 5, the body portion 10 is mounted upon a flat wooden support 50 and the jaws 13 and 14 engage therewith and will sink into the same. A single bolt 51 may now be employed, passed through the central opening 17, and carrying nut 52. One bolt will be sufficient under these conditions to suitably clamp the body portion 10 upon the flat wooden support 50.

The body portion 10 being now suitably held stationary the work will be held disposed within the open upwardly diverging V-shaped jaws 28. This work may be the handle 53 of a bush-ax which is elliptical in cross-section. This handle may be turned upon its longitudinal axis so that its maximum radial diameter may be disposed at any desired angle and the handle than clamped in the selected adjusted position. The hook 37 is inserted into the selected opening 32 or 34 while the tubular nut 44 is screwed down upon the bolt 40. The inverted V-shaped jaw being placed upon the upper side of the handle, the handle 46 is now turned and the tubular nut 44 will draw the bolt 40 downwardly, which in turn draws the jaw 35 downwardly into clamping engagement with the handle. Since the jaws 28 and 35 are all V-shaped, the elliptical handle is automatically centered therein regardless of the angular position of the maximum diameter of the same. These jaws will receive and hold

against slipping, work which is elliptical in cross-section, circular in cross-section, or other various shapes in cross-section. Since the jaws 28 are arranged at the ends of the web 11 they exert the maximum leverage for holding the handle against lateral displacement when the blade of the ax is being sharpened.

By virtue of the shape of the jaws 28 and 35 they will not injure or scar the handle, which is very important in connection with implements such as a bush-ax.

It is thus apparent that I have provided a portable vise which may be manipulated by a single operator and which will securely hold the work against displacement while it is being worked upon.

This application is a refile in part of my abandoned application for Toolholder and saw clamp, Serial No. 355,492, filed September 5, 1940.

20 It is to be understood that the form of my invention herewith shown and described is to be taken as a preferred example of the same and that various changes in the shape, size, and arrangement of parts may be resorted to without departing from the scope of the subjoined claims.

Having thus described my invention, what I claim is:

1. A portable vise comprising a substantially horizontal elongated body portion, upwardly 30 facing substantially V-shaped jaws mounted upon the body portion near its ends and spaced from each other throughout the major portion of the length of the body portion, a link arranged above the body portion and having a plurality of longitudinally spaced openings formed therein, said body portion having an opening formed therein near one longitudinal edge and generally equidistantly spaced from the V-shaped jaws, said body portion having a second opening formed therein near its opposite longitudinal edge and in substantial transverse alignment with the first named opening of the body portion, a loop mounted within the first-named opening of the body portion and freely 40 pivotally mounted within the end opening of the link, said link being foldable down flat upon the upper face of the body portion between the V-shaped jaws, an upper inverted substantially V-shaped jaw arranged between the lower 50 V-shaped jaws and provided at one end with a hook to be readily removably mounted within a selected opening of the link, an eye secured to the opposite end of the upper jaw, a rod having an eye having a permanent loose pivotal 55 connection with the first named eye, the rod extending through the other opening of the body portion and having a loose fit within the opening and projecting below the body portion, the upper jaw and rod being adapted to be dropped 60 so that the upper jaw will be in close relation to the upper face of the body portion when the upper jaw is disconnected from the link, a substantially vertical nut arranged beneath the body portion and having screw threaded engagement 65 with the rod, a tube connected with the nut to turn it, and a crank secured to the tube to rotate the tube.

2. A portable vise comprising a body portion adapted to be generally horizontally arranged, 70 upwardly facing spaced substantially V-shaped jaws mounted upon the body portion, a link arranged above the body portion and having a plurality of longitudinally spaced openings formed therein, a loop mounted upon the body portion between the substantially V-shaped jaws

and pivotally mounted within one opening of the link, the link being foldable down flat upon the upper face of the body portion between the jaws, an upper inverted substantially V-shaped jaw arranged between the lower jaws and provided at one end with a hook to be removably mounted within a selected opening of the link, a rod having pivotal connection with the upper jaw near the opposite end of such upper jaw, the body portion being provided between the lower jaws with an opening for receiving the rod which is longitudinally movable therein without turning upon its longitudinal axis, and a nut having screw threaded engagement with the rod and arranged beneath the body portion.

3. A portable vise comprising a body portion adapted to be generally horizontally arranged, upwardly facing spaced substantially V-shaped jaws mounted upon the body portion, a link arranged near and above the body portion and having a plurality of longitudinally spaced openings formed therein, mechanical means engaging within one opening of the link and secured to the body portion between the jaws and forming a universal connection between the link and body portion, the link being foldable down flat upon the upper face of the body portion between the jaws, an upper inverted substantially V-shaped jaw arranged between the lower jaws

and provided at one end with an extension to be removably mounted within a selected opening of the link, a rod having a permanent universal connection with the opposite end of the upper jaw, the body portion being provided between the lower jaws with an opening for receiving the rod which is longitudinally movable within such opening without turning upon its longitudinal axis, and a nut having screw threaded engagement with the rod and arranged beneath the body portion.
